MOP

Conrad Fatland, Mount Prospect, Ill.

Application January 23, 1935, Serial No. 3,064

6 Claims. (Cl. 15—119)

This invention relates to mop head wringers, and has for its object providing more conveniently for wringing the mop and for removing the mop from the mop head or inserting it therein. It has for a further object improved means for rendering inoperative the wringing means of the mop head; and another object is to provide an improved mop for the mop head.

Of the accompanying drawing, Fig. 1 is an elevation, partly in section of a mop head which embodies some of the features of my invention; Fig. 2 is a side view of the same; Fig. 3 illustrates a modified means for holding the crank handle of the wringer, and Fig. 4 is an edge view of the same.

The mop head in general is a common type, such as is shown and described in my Patents Nos. 1,966,890, 1,999,450, in which the two rollers 10 and 11 are journaled in the outer ends of the arms 12 and 13. These arms have transverse portions 14 and 15 by which the arms are fixed to the handle 16. The mop 17 in use is positioned between the rollers, and when desired the mop may be wrung by rotating the rollers. The rollers are rolled by means of a crank arm 18 which is fixed by one end to one of the spindles 19 of the inner roller 11. By means of a handle 18' the crank may be operated to rotate the roller 11.

This handle is pivoted to the free end of the crank arm so that it may be rotated outwardly with reference to the arm, and substantially at right angles thereto, when the mop is to be wrung. But this invention differs from those of the patents in that when the mop is in normal use the crank is rendered inoperative by turning the handle inwardly, as shown, and locking the free end of the handle in a depression 20 in the strip 21 which connects the arm 13 to the mop handle. The crank arm 18 is formed from strip metal and is somewhat resilient, and when the handle 18' is in the position shown the arm 18 is forced outwardly somewhat and its spring force holds the end of the handle firmly in the depression 20.

Suitable means are provided for guiding the end of the handle as it is being forced into the depression, such as the flanges 22 and 23, and a stop 24 may be provided to insure the end of the handle passing into the depression. It will be understood that the length of the handle is somewhat greater than the distance from the crank arm to the plate 21 before the arm is sprung outward.

If desired a depression 30 may be provided in the strap 31 for receiving the end of the handle, instead of the depression 20. In such a case the

handle 16 and the flange 32 form guides for directing the end of the handle 12 into the depression 30. This simplifies somewhat the operation as well as the mechanism.

In this mop head I provide means for conveniently separating the two rollers whenever it is desired to insert or remove the mop, or to vary the pressure on the mop. This means comprise the bars 33 and 34 which have their outer ends passing freely through the transverse portions 14 and 15, respectively, and the ends of the rollers are journaled in the other ends of the bars 33 and 34. This roller is journaled in the arms 12 and 13 in elongated slots 35 and 36, so that the roller can be moved a material distance longitudinally in the slots. Shoulders 37 and 38 are formed on the bars 33 and 34, and springs 39 and 40 are mounted on the respective bars between the shoulders and the transverse portions 14 and 15. These springs normally force the inner roller 21 against the outer roller. But the nuts 41 threaded onto the bars outside of the transverse portions 14 and 15 provide means for forcing the inner roller inwardly against the force of the springs.

By these means the rollers can be separated as much as may be desired, either for operation of the mop in wringing or for inserting or removing the mop. This also assists in removing or inserting the outer roller, which to be removed is forced inwardly until the flange 51 will pass through the opening 52 when the arms 12 and 13 are spread.

Any ordinary type of mop may be used; but I prefer one composed of two or more thicknesses, and having enlarged portions at the ends to prevent the mop from passing from between the rollers when it is being wrung. These portions may be formed by turning inwardly the ends 45, as indicated. The entire ends may be turned inwardly or only a narrow portion in any event by having the ends turned as indicated the water which is wrung from the mop passes down and off from the mop ends, as a fairly smooth surface is thus provided; while if the ends were turned outwardly the water would collect against the flat ends of the mop.

It will thus be seen that I have provided a mop that may be very quickly and conveniently operated. When it is desired to wring the moisture out of the mop it is necessary only to grasp the crank handle and pull it outwardly. To simplify this I provide an inclined surface 50 or 51' on the plate just outside of the depression or recess which receives the end of the crank handle. This

allows the end of the crank handle to be pulled outwardly without hindrance. The mop may then be wrung by merely revolving the handle outwardly. The enlargements on the mop will prevent it from being inadvertently forced from between the rollers, and if desired the pressure on the mop may be decreased by operating the nuts 41. Or if it is desired to remove the mop entirely from the rollers it is necessary only to separate the rollers sufficiently to allow the enlarged ends to pass between them.

In this type of mop head, as will be seen by a consideration of my said patents, the outer roller is removed by spreading the arms 12 and 13 and slipping the roller spindles from their bearings. This process is much simplified by separating the rollers by means of the nuts 41, as this relieves the pressure on the outer roller.

I claim as my invention:

- 20 1. A mop head wringer comprising a mop handle, a yoke-like pair of arms fixed to the handle, each pair having an outer and an inner opening adjacent its outer end, a pair of coacting rollers journaled in the respective outer and inner openings, the inner openings being elongated, the inner roller being movable longitudinally of the arms in the openings, each of said arms having a transverse portion, resilient means associated with the transverse portions normally pressing the inner roller towards the outer roller, and adjusting locking means associated with said resilient means for adjustably varying the minimum distance between the rollers when in use and which adjusting means comprises means to hold the inner roller in any one of a number of adjusted positions.
- 25 2. A mop head wringer comprising a mop handle, a yoke-like pair of arms fixed to the handle, each pair having an outer and an inner opening adjacent its outer end, a pair of coacting rollers journaled in the respective outer and inner openings, the inner openings being elongated, the inner roller being movable longitudinally of the arms in the openings, each of said arms having a transverse portion, resilient means associated with the transverse portions normally pressing the inner roller towards the outer roller and for varying the minimum distance between the rollers when in use, the said varying means comprising a bar positioned on the inner side of each of the yoke-like pair of arms and having one of its ends slideable in the transverse portion of the arm, the ends

of the inner roller being journaled in the ends of the respective bars, one of said bars having a portion passing outside of the said transverse portion, and a nut threaded on said projecting portion, outside of the transverse portion.

3. In a mop head wringer having a frame, a mop roller rotatably mounted in the frame, a mop handle fixed to the frame, means for rotating the roller and for preventing rotation thereof, said means comprising a resilient crank arm fixed to 10 the roller, a plate associated with one side of the mop handle and facing said crank arm, a crank handle pivoted by one end to the free end of the crank arm, the free end of said crank handle being rotatable inwardly into contact with said 15 plate, said crank handle having a greater length from its pivot than the normal distance from said pivot to said plate so that the rotation of the free end of said handle for a substantial distance in contact with said plate will force the resilient 20 crank arm away from the plate with the result that the resistance of said crank arm will press the free end of the crank handle against said plate and establish resistance to the movement of the 25 crank handle, the crank arm and the roller. 25

4. In a mop head wringer as claimed in claim 3, said means for preventing the rotation of the roller comprising a depression in said plate facing said crank arm and adapted to receive and hold the free end of said crank handle as it is yieldingly pressed towards the bottom of said depression by said resilient crank arm. 30

5. In a mop head wringer as claimed in claim 3, said means for preventing rotation of the roller comprising a depression in said plate facing said 35 crank arm and adapted to receive and hold the free end of said crank handle as it is yieldingly pressed towards the bottom of the depression by the resilient crank arm, and said plate having guide means for guiding the crank handle and into 40 the depression.

6. In a mop head wringer as claimed in claim 3, said plate having a depression therein and having guide means thereon for guiding the crank handle end into the depression, and means for limiting the inward movement of the crank handle end along said guide, said limiting means comprising a stop positioned adjacent the inner end of the 45 guide with reference to the mop head.

CONRAD FATLAND. 50
